UNITED STATES PATENT OFFICE

2,211,819

WALL SWITCH

Robert I. Innis, Winthrop, Mass.

Application June 10, 1939, Serial No. 278,512

9 Claims. (Cl. 200—168)

My invention relates to wall switches such as are installed in homes, offices and other places for controlling electric lighting circuits and the like, and to ornamental cover attachments for the same.

The invention has for its object to improve the construction and appearance of electric switches of the class indicated.

It is a further object of this invention to provide an improved wall switch of the type shown and described in my co-pending application filed January 3, 1938, Serial Number 183,081.

To these ends I have provided an improved wall switch of the class described which may have the features of construction and operation set forth in the following description, the several novel features of the invention being separately pointed out and defined in the claims at the close thereof.

20 In the accompanying drawing:

Figure 1 is a front elevation of a wall switch mechanism constructed in accordance with this invention, the cover, hereinafter described, being partly broken away.

25 Figure 2 is a section on line 2—2 of Fig. 1.

Figure 3 is a front view of the face plate hereinafter described.

Figure 4 is a top plan view of the rocker member hereinafter described.

30 Figure 5 is a side view of the rocker member shown in Fig. 4.

Figure 6 is a section on line 6—6 of Fig. 5.

Figure 7 is a side view of the spring clamp hereinafter described.

35 Figure 8 is an elevation showing another side of the spring clamp shown in Fig. 7.

Figure 9 is a detail showing one of the coupling studs hereinafter described.

Figure 10 is a side elevation of one of the 40 coupling yokes hereinafter described.

Figure 11 is a section on line 11—11 of Fig. 10.

Figure 12 illustrates an alternative construction.

45 Figure 13 is a detail, on reduced scale, of the link hereinafter described.

A common form of wall switch comprises a porcelain body 10 equipped with a metal bridge-bar 12 which is fastened by screws at its opposite ends to a metal switch box 13, said box being incorporated within a wall 14. The body 10 contains the make and break mechanism of the switch, as usual, and in Figs. 1 and 2 this mechanism is operated by means of two push-buttons 15 and 15', while in Fig. 12 it is operated by a 55 lever 16. Ordinarily the bridge-bar 12 is pro-

vided with threaded apertures at 18, 18 to receive two screws by means of which a face plate is secured to the bridge-bar 12 and held in position against the surface of wall 14, the marginal portion of said face plate over-lying the part of 5 the wall adjacent to the box 13.

In accordance with the present invention I provide a special face plate 17, Figs. 2 and 3, which is made with two apertures 18a to register with the apertures 18 of bridge-bar 12. These apertures 18a accommodate screws 11 which are screwed into the apertures 18 of bridge-bar 12 to secure the face plate in position against the wall. The face plate 17 is preferably molded from sheet metal and bordered by a skirt 17a 15 which fits edgewise against the wall.

At its middle the face plate 17 is made with an elongate aperture or slot 25 through which the push-buttons 15 and 15' move back and forth when the switch is operated. At each side of 20 slot 25 the flat middle portion or web of face plate 17 is made with a perpendicular apertured tang 31 and between these two tangs is arranged a rocker member 19 shown in detail in Figs. 4, 5 and 6, said rocker member being made from 25 sheet metal and comprising a pair of relatively parallel apertured legs 32 which are pivotally connected with the tangs 31 by a pintle 20. The two legs 32 are connected at their outer free ends by a flat intermediate portion 34 made at opposite 30 sides thereof with arms 33 each of which has its free end disposed opposite the outer end of one of the push-buttons 15 or 15'.

The axis of pintle 20 is disposed transversely with respect to slot 25 midway between the two 35 push-buttons so that when the rocker 19 is swung on the axis of pintle 20 in one direction push-button 15 is forced inwardly and when swung on said axis in the opposite direction push-button 15' is forced inwardly, it being understood that switch mechanism within body 10 40 is constructed, as usual, so that when one button is forced inwardly the other button is moved outwardly by said mechanism.

With different switches of the push-button 45 type I find that the buttons thereof do not always project through or beyond the face plate exactly the same distance. That is to say, the distance the buttons project beyond the face plate of different switches often varies as much as one-eighth of an inch and in order to provide for this variation I have found it desirable to provide a resilient support for the rocker member 19 such as leaf springs 21, Fig. 3, which are of sufficient 50 stiffness to ensure operation of the push-buttons 55

by the rocker member and yet sufficiently resilient to permit the rocker member to fit itself to the push-buttons whatever be the relation of the latter to the face plate 17. In the present instance, the leaf springs 21 are two resilient tangs produced by forming the web of the face plate 17 with angular slits 38 each of which opens into the slot 25 alongside of the tangs 31 and these rocker-supporting tangs are disposed one at each side of the lower push-button 15' and rocker 19.

Adjacent to its lower end the web of face plate 17 is formed with a pair of perpendicular apertured tangs 35 between which is fitted the hub portion of a hand lever 23 which is pivotally connected with said tangs by means of a pintle 22, Fig. 2. This lever 23 is connected by a link 24 with the rocker member 19 so that when said lever is swung on its fulcrum 22 it acts through the link to swing the rocker member on its pivot 20. It will be clear that when hand lever 23 is swung downwardly it will act through link 24 to swing rocker 19 downwardly also and cause the same to force the push-button 15' inwardly and this inward movement of push-button 15' is accompanied, as usual, by corresponding outward movement of push-button 15. It will also be clear that when hand lever 23 is swung upwardly into the position shown it will act through the link 24 to angularly adjust rocker 19 on its pivot 20 in a direction to force push-button 15 inwardly and push-button 15' outwardly.

As shown in Fig. 13 the link 24 is a bail-shaped member formed from wire and comprising an intermediate portion, two parallel side bars, one 35 at each end of said intermediate portion and two inwardly bent trunnion portions 36 at the free ends of said side bars. The intermediate portion 27 of the link is pivotally mounted within slots 26 formed in the rocker member 19 while the 40 trunnion portions 36 are pivotally mounted within the opposite ends of one of a series of holes or sockets 37 formed transversely through lever 23. The holes or sockets 37 are positioned at different distances from the pivot or fulcrum 22 so that the extent of movement imparted to link 24 by said lever may be regulated according to the instrumentality that is operated by the link.

The slots 26 of rocker member 19, Figs. 4, 5 and 6, are formed partly in the legs 32 and partly 50 in the intermediate portion 34 of the rocker member. This permits one end of the wire link to be threaded through the slots 26 until the intermediate portion 27 thereof occupies said slots without injurious distortion of the link. After 55 thus connecting the link with the rocker member 19 the laterally and inwardly bent trunnion extremities 36 are sprung into the opposite ends of one of the holes 37 of lever 23.

For inclosing, shielding and concealing from 60 view the above described switch mechanism I provide a cover 28 constructed with a skirt 30 whose chime fits edgewise against wall 14 throughout the circuit of said cover and outside of face plate 17. This construction also provides 65 a chamber 29 that is occupied by rocker 19, link 24 and lever 23.

Cover 28 is preferably a molded product produced from any suitable material such, for example, as a phenolic-condensation product, hard 70 rubber or the like and as herein shown said cover is provided upon its interior with a pair of spaced apart studs 39 for engagement with spring socket members 40 fixed in position upon the outer side of face plate 17, thereby to removably secure the 75 cover in position against the wall 14.

Adjacent to its lower end the cover 28 is made with a slot 41 through which the handle portion of lever 23 projects to the exterior of the cover where it is accessible for manual operation. This slot is of sufficient length to permit of the necessary extent of movement of lever 23 and its opposite ends may serve as stops for said lever. The portion of lever 23 within the cover 28 is made with arcuate lateral extensions or portions 42 at opposite sides thereof which serve at all times to close the slot 41. The outermost faces of these extensions 42 are formed concentrically with respect to the fulcrum 22 and one or the other of said extensions is at all times in position to close the slot 41.

Each spring socket member 40 is a spring metal yoke whose intermediate portion is formed with an aperture through which the shank of one of the screws 11 extends as shown in Figs. 10 and 11. The arms of the yoke are bent inwardly somewhat around the head of the screw 11 and their relatively parallel free end portions are formed with oppositely disposed apertures 43 which provide sockets for the reception of a ball-like head 44 provided on the stud 39 which cooperates with the spring socket member. Each stud element 39 has a shank portion fixedly embedded within the material of cover 28 and in applying the cover to the switch mechanism the heads 44 of the stud elements 39 are placed against the outer 30 ends of the spring arms of the yokes 40 and then forced into position between said arms so that said heads occupy the socket apertures 43 as shown in Fig. 2. As will be clear the cover 28 may be removed when desired by pulling outwardly thereon. It will also be clear that the lever 23 is free to enter, or to be withdrawn from, the slot 41 as the cover is placed in position or removed.

In the embodiment of my invention illustrated in Fig. 12 the switch is constructed with an operating member 16 in the form of a lever and to this lever I apply a spring clamp 45 which is shown in detail in Figs. 7 and 8. This clamp consists of a yoke made from spring metal and comprises two lever-gripping arms 46 and 47, the former made with a transverse socket 48 to receive the intermediate portion 27 of the link 24, Fig. 13, and the latter being made near its free end and upon its inner side with a re-entrant tooth 49. The intermediate portion 27 of link 24 is sprung into the socket 48 and then the spring clamp 45 is forced on to the lever 16 into the position shown in Fig. 12 where it holds itself in position through the gripping action of the arms or jaws 46 and 47. The extremity of the jaw 46, adjacent to socket 48, is also made with a re-entrant tooth 50. When the spring clamp is forced on to the lever 16 the teeth 49 and 50 hold the same against slipping outwardly off from the lever. Otherwise the wall switch illustrated in Fig. 12 may be constructed as already described in connection with Figs. 1 and 2.

It will be clear that the spring clamp 45 will accommodate itself to levers 16 of different sizes.

The extent of movement necessarily imparted to link 24 to operate lever 16 will be greater than that required for the type of switch illustrated in Fig. 2, but as will be clear the trunnion extremities 36 of the link 24, Fig. 13, may be positioned within the appropriate hole 37 to ensure the desired extent of movement.

Another advantage to the above described construction is that the ends of the slot 41 may and preferably do provide positive stops for limiting 75

the swinging movement of lever 23 thus avoiding undue strain upon link 24 and rocker 19. The above described provision for adjustment of the connection between link 24 and lever 23 also 5 provides for adaptation of the actuating mechanism to variations found in different models of wall switches of the same type.

The above described construction provides several desirable improvements upon the constructions illustrated and described in my co-pending application, referred to above, and also in my Patent No. 2,146,146 granted February 7, 1939.

What I claim is:

1. The combination with a wall switch of the character described comprising a body adapted to be fixed within a cavity of the wall, an apertured face plate fixed to said body whose marginal portion overlies the outer face of the wall adjacent to said cavity, and switch-operating mechanism projecting from said body through the aperture of said face plate to the exterior thereof, of mechanism for actuating said switch-operating mechanism including a lever fulcrumed directly on said face plate, a hollow cover having an outer parts-concealing wall made with an aperture and also made with a skirt which entirely surrounds said face plate with its chime adjacent to said wall, and means by which said cover is attached to said face plate, 30 said cover enclosing and entirely concealing said switch-operating mechanism, said cover-attaching means and all of said actuating mechanism with the exception of a portion of said lever which extends through the aperture of the cover 35 to the exterior thereof where it is accessible for manual operation.

2. The combination of claim 1 wherein said lever is made with arcuate lateral extensions projecting from opposite sides thereof which are 40 within said cover and concentric with the fulcrum of said lever so as to serve as closures for the unoccupied portion of said aperture when the lever occupies a position at the limit of its movement in either direction.

45 3. The combination of claim 1 wherein the means for attaching the parts-concealing cover element to the face plate element consists of studs on one of said elements and spring sockets on the other of said elements which separably grip said studs to hold said cover element in position and which are engaged with and disengaged from said studs by bodily movement of said cover element toward and from the wall.

4. The combination of claim 1 wherein the 55 means for attaching the parts-concealing cover element to the face plate element consists of studs on one of said elements each of which is made with a head, and spring sockets on the other of said elements each of which comprises a pair of apertured resilient jaws which separably grip and interlock with the heads of said studs to hold said cover element in position, said studs and sockets being engaged and disengaged by bodily movement of said cover element toward 60 and from the wall.

5. The combination of claim 1 wherein the apertured face plate is fixed to said body by the usual pair of screws, and wherein the means for attaching the parts-concealing cover element to said face plate element consists of studs partly 5 embedded within the material of the cover element and projecting therefrom upon the interior of the latter, and spring sockets fastened in position upon the outer side of said face plate by said screws, each socket comprising a pair of 10 resilient jaws for separably gripping and holding one of said studs, and said studs and sockets being engaged and disengaged by bodily movement of said cover element toward and from the 15 wall.

6. The combination of claim 1 wherein the switch-operating mechanism projecting outwardly from the switch body consists of a pair of push-buttons; wherein said actuating mechanism includes a rocker member for operating said push-buttons, said rocker member being pivotally mounted upon the free ends of a pair of resilient tangs forming integral parts of said face plate, and wherein a link is provided by which said 20 rocker member is connected with the lever of 25 claim 1.

7. The combination of claim 1 wherein the switch-operating mechanism projecting outwardly from the switch body consists of a pair 30 of push-buttons; wherein said actuating mechanism includes a rocker member for operating said push-buttons, wherein said face plate is made with a pair of slits opening into the aperture of said plate whereby to provide a pair of leaf 35 springs by which said rocker member is pivotally and resiliently supported, and wherein a link is provided by which said rocker member is connected with the lever of claim 1.

8. The combination of claim 1 wherein the switch-operating mechanism projecting outwardly from the switch body consists of a lever arm; wherein a U-shaped spring clamp is provided which embraces and grips said lever arm with its intermediate portion opposite the outer end of the latter, said spring clamp being made 45 with a transverse socket, and wherein a bail-shaped link is provided by which said spring clamp is connected with the lever of claim 1, the intermediate portion of said link occupying said socket, and its two opposite side portions 50 being pivotally connected at their extremities with the lever of claim 1.

9. The combination of claim 1 wherein the lever of said actuating mechanism is made upon each side thereof with a plurality of sockets disposed at different distances from the fulcrum of said lever and wherein said actuating mechanism also comprises a bail-shaped link through which said lever acts to actuate said switch-operating mechanism, the extremities of the opposite side 60 portions of said link embracing said lever and being made with laterally extending trunnions occupying sockets at opposite sides of said lever.
